UNITED STATES PATENT OFFICE.

JAMES F. SARGENT, OF LOWELL, MICHIGAN.

CLOTHES-BASKET.

1,199,714.

Specification of Letters Patent. Patented Sept. 26, 1916.

Application filed January 20, 1916. Serial No. 73,265.

To all whom it may concern:

Be it known that I, JAMES F. SARGENT, a citizen of the United States, residing at Lowell, in the county of Kent and State 5 of Michigan, have invented certain new and useful Improvements in Clothes-Baskets, of which the following is a specification.

My invention relates to improvements in 10 latches for securing the legs of folding legged clothes baskets in extended position, and its objects are; first to confine the latch or fastening necessary for this purpose exclusively to the bottom of the basket; sec- 15 ond, to avert the necessity of providing a long actuating handle with locking devices at the upper edge of the basket, thus disfig- 20 uuring the ends of the basket, and, third, to greatly simplify the manipulation of the 25 folding legs. I attain these objects by the mechanism, construction and mode of operation shown in the accompanying drawing, in which—

Figure 1 is an elevation of a basket and 25 folding legs, with the legs extended; Fig. 2 is an end view of a basket base showing the form of the feet and of the latch and its several connecting elements, and, Fig. 3 is a side elevation of the latch or spring de- 30 tached.

Similar reference numerals indicate simi- 35 lar parts throughout the several views.

In Fig. 1, 1 represents the basket body; 2 is the longitudinal base cleat, of which 35 there should be several secured upon the bottom of the basket. The cross cleats are firmly secured to these cleats, as indicated at 4, and, in turn, the cleats 3, 3 to which the legs 8 are secured, are pivotally con- 40 nected with the cleats 4, 4, as indicated at 7, 7. These cleats, 3, 3 should be slightly beveled or tapered outward, as indicated, for the purpose of throwing the lower ends 45 of the legs considerably out of the vertical, or flaring from the bottom of the basket outward. 11, 11 represent ordinary heli- 50 cal springs properly connected with the cleats 3, 3 and the basket body to draw the legs 8, 8 up into folded position against the bottom of the basket, as indicated by the dotted lines in Fig. 1.

My securing element, or latch, consists of a spring 5, one end of which is secured to the base cleat between this cleat and the 55 cross cleat 4, as at 10, so this end of the

spring will be held rigidly in place while the other end of the spring is passed under the edge of the cross cleat 4 in such a manner that by pressing upon the spring 5 at 12 the catch 6 will be drawn off of the loop 9 60 and the cross cleat 3 will be released and the spring 11 will draw the legs up into folded position, as hereinbefore mentioned.

The outer ends of the cleats 3, 3 are made to project considerably below the body of 65 the cleat for the purposes: first, of providing sufficient space between the edges of the cleats and the ends of the projections to safely contain the staples 9 without danger of these staples coming in contact with the 70 floor when the legs 8, 8 are folded for storing the baskets, and, second, to provide a short leg at each corner of the basket for the basket to stand upon when the legs 8, 8 are folded under the basket.

The staples, or loops 9, are secured into the 75 ends of the cleats 3, 3 and arranged to pass just outside of the spring catch 5, but the catch 6 on the spring 5 must project far enough beyond the body of the loop or 80 staple 9 to form a rigid catch to engage the body of the staple when the legs are extended, and thus to hold the legs firmly in place when extended, the staple being so arranged that as the legs 8, 8 are swung outward into 85 vertical, or practically vertical position, the staple 9 will force the catch 6 backward so the staple can pass over the catch 6 on the spring 5 and the spring 5 will then force the catch 6 outward into position to engage 90 and hold the staple and, with it, the legs in the desired extended positions.

The objects for making a sliding bearing for the end 14 of the spring latch 5 are: 95 first, to provide for the easy working of the spring to release the staple 9 when desired, and, second, to avert the danger of the end 14 of the spring being drawn away from the bottom of the basket by the movement 100 of the basket along the floor with the legs extended, or by the strong tension of the springs 11, 11 when the legs are extended. I desire to have it understood, also, that when the spring latches 5, 5 are not made too heavy it may not be necessary to allow the end 14 to slide, as sufficient flexibility 105 may be allowed in the spring to render it possible to bend the spring back far enough to release the staple from under the point of the latch at 6.

What I claim as new, and desire to secure by Letters Patent of the United States, is:—

1. In combination with a clothes basket 5 cross cleats secured to the bottom thereof, legs pivotally secured to said cleats in pairs, and springs connected with the legs to draw them into folded position on the bottom of the basket; a spring latch securely connected 10 at one end with each bottom cleat of the basket, and the other end slidingly connected therewith, a catch near the sliding end of each latch, and means connected with the legs to be made to engage said catches 15 when the legs are in extended position.
2. In combination with a clothes basket, longitudinal cleats on the bottom of the basket, cross cleats secured to the longitudinal cleats, legs connected upon a cleat, said 20 cleat pivotally connected with the cross cleats for the free movement of the legs pivotally therefrom, and springs for moving the legs into folded position against the bottom of the basket; flat spring latches

secured at one end to the bottom cleats of the 25 basket, and at the other end slidingly secured to the bottom of the basket, a catch formed near the sliding end of each latch, a staple secured in the edge of each leg supporting cleat in position to be made to engage said 30 catches when the legs are extended and hold the legs in extended position.

3. In combination with a clothes basket having folding legs and springs for drawing the legs into folded position, cleats connecting the legs in pairs, staples secured to the edges of the cleats, semicircular spring latches connected with the bottom of the basket and passing over the leg connecting cleats, the staples in the edges of said cleats 40 in position to be made to engage the latches and hold the legs in extended position, said latches arranged to be readily disconnected from the staples, as and for the purpose set forth.

Signed at Lowell Michigan January 17th
1916.

JAMES F. SARGENT.
